UNITED STATES PATENT OFFICE.

GIO BUTON, OF BOLOGNA, ITALY.

DESIGN FOR A BOTTLE.

No. 38,139.

Specification for Design.

Patented July 31, 1906.

Application filed April 17, 1906. Serial No. 312,269. Term of patent 14 years.

To all whom it may concern:

Be it known that I, Gio BUTON, a subject of the King of Italy, residing at the city of Bologna, in the Province of Bologna, Italy, have invented a new, original, and ornamental Design for a Bottle, reference being had to the accompanying drawing.

The figure is a perspective view of a bottle showing my new design.

I claim—

The ornamental design for a bottle, as shown.

GIO BUTON.
